UNITED STATES PATENT OFFICE.

ROBERT KROEDEL, OF ROCHESTER, NEW YORK, ASSIGNOR TO EASTMAN KODAK COMPANY, OF ROCHESTER, NEW YORK, A CORPORATION OF NEW YORK.

FOLDING CAMERA.

1,380,810.

Specification of Letters Patent. Patented June 7, 1921.

Application filed December 13, 1919. Serial No. 344,558.

To all whom it may concern:

Be it known that I, ROBERT KROEDEL, of Rochester, in the county of Monroe and State of New York, have invented certain 5 new and useful Improvements in Folding Cameras; and I do hereby declare the following to be a full, clear, and exact description of the same, reference being had to the accompanying drawings, forming a part of 10 this specification, and to the reference-numerals marked thereon.

My present invention relates to photography and more particularly to photographic cameras of the folding type in 15 which a bellows and front or lens mount are projected from an inoperative position within the body to an operative position over a hinged bed that forms a door for the body and the invention has for its object to 20 provide an improved means for holding the lens mount or front securely in its operative position. The improvements are also directed toward providing a convenient means for releasing the lens mount and means 25 whereby the release thereof automatically releases the bed to permit it to fold. To these and other ends the invention resides in certain improvements and combinations of parts all as will be hereinafter more fully 30 described, the novel features being pointed out in the claims at the end of the specification.

In the drawings:

Figure 1 a side view of a folding camera 35 constructed in accordance with and illustrating one embodiment of my invention, the same being in operative position.

Fig. 2 is a similar view showing the camera partially folded;

Fig. 3 is a central longitudinal section 40 through the bellows chamber showing the parts folded but with the rest of the body omitted;

Fig. 4 is a horizontal section through the body on the line 4—4 of Fig. 1, with the bellows removed and showing the bed and related parts in top plan view;

Fig. 5 is a front view, and

Fig. 6 is an enlarged fragmentary, longitudinal central section through the front portion of the bed.

Similar reference numerals throughout the several views indicate the same parts.

Referring more particularly to the drawings, 1 indicates the body and 2 the door and

bed hinged to the body at 3 to swing from the inoperative position of Fig. 3 to the operative position of Fig. 1, and 4 is the bellows and 5 the lens board or front upon which the lens 6 and shutter 7 are carried and hereafter called the lens mount. The bellows chamber 6^a within the body is defined by the frame 7^a and accommodates the bellows and lens mount, as shown in Fig. 3, when folded therein in the manner hereinafter 65 described.

In the practice of my invention, I provide a folding brace 8 for supporting the bed from the body in operative position much in the usual way, except that the brace is released by an upward or forward instead of the customary downward and rearward movement. The lower end thereof is pivoted at 9 in each instance (there being one brace on each side of the camera) to an upwardly 75 turned ear 10 on the edge of the bed 2, while its upper end is slotted at 11 to run on a headed pin 12 on the inner side of a side wall of the body 1, when the bed is folded. The locking shoulder that coöperates with 80 the pin when the latter is at the end of the slot to resist upward movement of the bed is indicated at 13 and the end of the brace is split as at 14 to give the desired spring tension for holding the pin and shoulder in 85 engagement.

The lens mount or board 5 has forwardly turned lateral ears 15 located approximately at its center line and by means of which it is pivoted at 16 to the upper ends of two 90 supporting links 17 the lower ends of which are pivoted at 18 to forward and laterally arranged upstanding ears 19 on the bed. When the camera is folded, the supporting links 17 swing rearwardly, as shown in Fig. 95 2, on their pivots 18 and the lens mount 5 moves bodily with them but it also rotates forwardly on its other pivot 16 so that it folds face down against or substantially parallel with the bed 2 as the links reach a 100 similar position.

The lens mount and its pivotal support are held rigidly in the erect operative position by a pair of jointed links the parts 20 and 21 of which are pivoted together at 22 105 while the first mentioned is pivoted to the bed at its other end on the same pivot 9 that carries the link 8. The joint 22 between the parts of each brace is an elbow joint and is broken in a downward direction, 110

as shown in Fig. 2, to permit the rearward swing of the supports 17. As it is straightened to an operative position, it is prevented from passing the dead center in the other 5 direction with respect to the pivot 9 and a pivot 23 that connects the member 21 of the base to the supporting links 17 by an extension 24 on the member 20 having an in-turned flange 25 engaging the member 21. 10 It will be seen that in unfolding or extending the camera, as in Fig. 2, the short radius upon which the pivot 9 revolves around the hinge 3 causes the brace 20-21 to straighten and erect the lens mount supporting links 15 17, as in Fig. 1.

The braces 20-21 are released to permit the folding of the lens mount and its supports by a natural rearward pressure at the front of the lens mount that, continued, 20 folds down the supports 17 while the resistance of the bellows or contact with the camera body starts the lens mount itself rotating forwardly on its pivot 16 and this releasing operation also releases or unlocks 25 the braces 8 between the bed and body. It is accomplished by pressing with the thumbs against two bell crank extensions 24^a of the brace members 21 that extend upwardly at the sides of the supports 17 and forwardly 30 of the lens mount. The braces 8 adjacent the pivots 9 thereof are provided with forward extensions 25^a having inturned ears 26 located against the under sides of the members 20 of the front braces. When these 35 members swing downwardly in the folding operation just described, they press on the ears 26 and rock the braces 8 forwardly so that the shoulders 13 disengage from the pins 12 on the body and allow the braces 8 40 to fold and the bed 2 to swing toward the body.

It is necessary that means be provided for carrying the lens mount 5 to a true erect position on its pivotal connections 16 with 45 the supports 17 when the latter have been erected by the braces 20-21 and in the present instance, I provide for this purpose on the inner side of each link support 17 a finger 27 pivoted thereto at 28, as best shown 50 in Fig. 6. When the parts are in other than the operative or extended position of Figs. 1 and 6, these fingers are held spread rearwardly, as shown in Fig. 2, to catch beneath lateral arms 29 on the lower edges of the 55 lens mount 5 as the latter swings upwardly on the links 17 by leaf springs 30 fastened to the links at 31 and which leaf springs engage lugs 31^a on the fingers near their pivots 28. As the links 17 reach their erect position, shoulders 32 on the opposite sides of the centers of the fingers 27 come up against abutments 33 formed, in the present instance, as extensions on the ears 19 and carry the extensions 29 on the lens mount tight 60 against the rear edges of the supporting 65

links 17, as shown in Fig. 6, so that the lens mount can no longer turn on its pivot 16 in either direction. In this position, the springs 30 remain under tension and are ready to kick the fingers 27 out of the way 70 to permit the folding of the mount 5 as soon as the breaking of the joint in the brace 20-21 has swung the link supports 17 rearwardly to carry the shoulders 32 of the fingers away from the abutments 33. 75

I claim as my invention:

1. In a folding camera, the combination with a body, a bed hinged thereto and a lens mount pivotally supported on the bed, of a jointed brace for the lens mount pivoted to 80 the bed and a device for breaking the joint of the brace.

2. In a folding camera, the combination with a body, a bed hinged thereto, a folding lens mount and means on the bed for 85 pivotally supporting the lens mount, of a jointed brace for the lens mount pivoted to the bed and to said means and operating devices at the front of the lens mount for breaking the joint of the brace. 90

3. In a folding camera, the combination with a body, a bed hinged thereto, a folding lens mount and means on the bed for pivotally supporting the lens mount, of a jointed brace for the lens mount pivoted to the bed 95 and to said means, one member of the jointed brace being provided with a rigid extension at the front of the lens mount adapted to be pressed to break the joint of the brace.

4. In a folding camera, the combination 100 with a body, a bed hinged thereto to fold rearwardly against the body, a lens mounted adapted to fold rearwardly to a position substantially parallel with the bed and links pivoted to the latter and pivotally supporting the lens mount, of a jointed brace for the lens mount pivoted to the bed and to the links, one member of the jointed brace being provided with a rigid extension at the front of the lens mount adapted to be 105 pressed rearwardly to break the joint of the brace. 110

5. In a folding camera, the combination with a body, a bed hinged thereto to fold rearwardly against the body, a lens mount 115 adapted to fold rearwardly to a position substantially parallel with the bed and links pivoted to the latter and pivotally supporting the lens mount, of a jointed brace for the lens mounted pivoted to the bed and to the links, one member of the jointed brace being provided with a rigid extension at the front of the lens mount adapted to be 120 pressed rearwardly to break the joint of the brace, and a folding brace connecting the bed and body and adapted to be released by the jointed brace when the latter is broken. 125

6. In a folding camera, the combination with a body, a bed hinged thereto, and means for locking the bed in extended posi- 130

tion, of a folding lens mount on the bed and means for holding it in operative position and adapted when released to also release the locking means.

5 7. In a folding camera, the combination with a body, a bed hinged thereto and a folding brace connecting the bed and body and having a locked position when the camera is extended, of a folding lens mount 10 and a brace connected to the bed for holding the lens mount in operative position and adapted when released to also unlock the first mentioned brace.

15 8. In a folding camera, the combination with a body, a bed hinged thereto and means for locking the bed in extended position, of a folding lens mount on the bed and a two part jointed brace for holding it in operative position and adapted when released to 20 release the said locking means, one part of said brace being extended forwardly of the lens mount to constitute an operating portion for breaking the joint of the brace.

25 9. In a folding camera, the combination with a body, a bed hinged thereto and means for locking the bed in extended position, of a folding lens mount on the bed and a two-part jointed brace for holding it in operative position, one part of said brace constituting 30 an operating portion for breaking the joint

and releasing the lens mount and the other part being arranged to coöperate with the bed locking means and to release it also.

10. In a folding camera, the combination with a body, a bed hinged thereto and a folding brace for locking the bed in extended position, and having one end pivoted to the bed and provided with an extension beyond the pivot, of a folding lens mount on the bed and a two part jointed brace for holding 35 it in operative position, one part of said brace constituting an operating portion for breaking the joint and releasing the lens mount and the other part being arranged to coöperate with the extension on the bed 40 brace to release it.

11. In a folding camera, the combination with a body and a bed hinged thereto, of a lens mount support pivoted to the bed on a fixed pivot to fold rearwardly against the 50 same and two members operating to erect the support automatically as the bed is extended, said members being pivoted together and one of them being pivoted to the lens mount support and the other being pivoted to the bed on a shorter radius from the hinge thereof than that of the pivot connecting the support to the bed.

ROBERT KROEDEL.
